TRIMMING MACHINE

Hans Hacklander, Linden, N. J., assignor to The
Singer Manufacturing Company, Elizabeth,
N. J., a corporation of New Jersey

Application July 15, 1944, Serial No. 545,061

19 Claims. (Cl. 164—49)

1

This invention relates to cloth trimming machines, as of the kind suitable for trimming off imperfectly seamed portions of stockings and for other purposes; and has for its primary object to provide an improved machine of this character capable of operating at high speed and so organized as to effect the severing or trimming of the material fed through the machine, in a highly efficient manner and with a minimum amount of attention by the operator.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings,

Fig. 1 is a front elevation of a trimming machine embodying the invention, with the outer feed-cup removed and a portion of the overhanging bracket broken away;

Fig. 2 is a side elevation with a portion of the machine frame broken away;

Fig. 3 is a vertical transverse sectional view taken through the machine-frame and illustrating the main-shaft and some of the connections actuated thereby;

Fig. 4 is a vertical longitudinal sectional view taken through the machine-frame and illustrating the trimmer-bar and feeding mechanisms;

Fig. 5 is a top plan of the machine, with the cover-plate removed and showing the belt-drive for the outer feed-cup;

Fig. 6 is an enlarged view in side elevation of the pivotally mounted feed-cup supporting lever for the outer feed-cup;

Fig. 7 is a horizontal sectional view taken through the machine-frame substantially on the line VII—VII of Fig. 4;

Fig. 8 is an enlarged sectional view substantially on the line VIII—VIII of Fig. 7;

Fig. 9 is an enlarged sectional view of the cutter blade supporting mechanism and associated parts;

Fig. 10 is a sectional view substantially on the line X—X of Fig. 9; and

Fig. 11 is a bottom plan view of the machine with the lower cover-plate removed, showing the clutch and gear-drive for the feed-cups.

Referring in detail to the drawings, the present illustrated embodiment of the invention includes a machine-frame generally designated 1 and including a standard 2 and a laterally projecting overhanging bracket 3. Formed as an integral part of the standard 2 and disposed beneath the overhanging bracket 3 is an extension 4 and a supporting lug 5, the latter sustaining the inner

feed-cup 6 of the feeding mechanism and the extension providing a housing for some of the actuating connections for the inner feed-cup 6. Co-operating with the inner feed-cup 6 is an outer feed-cup 7 which depends from the overhanging bracket 3. Removably secured upon the bracket 3 is a cover-plate 8 which is secured by means of a screw 9.

Adjacent the top of the standard 2 is a horizontal partition 10 which divides the machine-frame into a splash-lubrication compartment 11 and a belt compartment 12, see Figs. 3 and 4. The splash-lubrication compartment 11 is closed at the bottom by means of a plate 13 secured by screws 14 and sealed by a gasket 15.

Disposed in the splash-lubrication compartment 11, transversely of the machine-frame, is a main-shaft 16 journaled in bushings 17, Fig. 3, fixed in flanged sleeves 18 secured by screws 19 in bosses 20 cast in the standard 2. Mounted on the opposite ends of the main-shaft 16 are balance-wheels 21 each having a belt-groove 22. Each flanged sleeve 18 is formed with an oil-port 23 in register with a slot 24 in the boss 20 and an oil inlet port 25 in the bushing 17, whereby oil is introduced into the shaft bearing. To prevent leakage of oil, the main-shaft 16 at its opposite ends is provided with spiral grooves 26 which feed the excess oil in the shaft bearing back into the splash-lubrication compartment 11. In addition to this oil-guard, the flanged sleeve 18 is provided with an undercut circular recess 27 entered by a reduced hub portion 28 of the balance-wheel 21. Formed in the reduced portion 28 are several circular oil-collecting grooves 29. In the event that some oil should leak onto the balance-wheel 21, this oil is collected in the grooves 29 and is thrown off by centrifugal force into the undercut recess 27 and is returned into the splash-lubrication compartment 11 by a return port 30 formed in the lower portion of the flanged sleeve 18.

The main-shaft 16, as shown in Figs. 3 and 7, is formed with a crank, in addition to having secured thereto an eccentric, whereby the below-described connections within the compartment 11 are actuated.

From Fig. 4, it will be seen that the connections actuated by the main-shaft 16 and extending below the same dip into oil, whose normal level is shown by the line L in Fig. 4, contained in the lower portion of the standard. These connections, during the operation of the machine, splash the oil throughout the lubrication compartment 11 of the machine and thereby thoroughly lubricate the mechanism contained therein. The level of the oil may be inspected from time to time, and preferably through a transparent window 31 having thereon a horizontal line 32 indicating the correct level of the oil.

Located in the belt compartment 12, see Fig.

5, is a conventional clip-belt 33 for actuating the outer feed-cup 7, the pivotally mounted supporting lever 34 for the outer feed-cup 7, and a lighting attachment 35.

From the above description, it will be understood that there is provided a machine-frame divided into two compartments, one of which is oil-tight and houses all the actuating mechanism operating at a high rate of speed, while the other of which is opened to the atmosphere and houses some of the actuating mechanism operating at a slower rate of speed. The primary advantage of such a construction is that the mechanism operating at high speed can be splash-lubricated, while the mechanism operating at slow speed need not be splash-lubricated.

The work is adapted to be fed, intermittently, through the machine in substantially a vertical plane, by means of the inner feed-cup 6 and the outer feed-cup 7. Referring particularly to Fig. 4, it will be seen that the inner feed-cup 6 is secured by a screw 36 upon the upper reduced end-portion of a vertical feed-shaft 37 which is journaled in spaced bushings 38 and 39 fixed in the frame-lug 5 and the extension 4, respectively. Forming a housing for the vertical feed-shaft 37 is a relatively thin stationary tube or sheath 40 of which the upper end is fixed in the extension lug 5 and the lower end is fixed in the extension lug 4. The tube 40 serves as a guard for preventing the work from becoming wound upon the feed-shaft 37 as the latter is rotated and also, since the tube has a tight fit in the extension 4, the oil in the machine-frame 1 may rise in the tube 40 to the same level as the oil in the machine-frame, thereby lubricating the lower bearing for the feed-shaft 37. The upper bearing is lubricated by hand through a central bore 41 and radial duct 42, the oil being distributed throughout the length of the bearing by the spiral oil-groove 43 cut into the feed-shaft 37.

The feed-shaft 37 has fastened upon its lower end-portion a spur gear 44 which meshes with a second spur gear 45 secured to the lower end of a vertically disposed feed-actuating shaft 46 journaled within the splash-lubrication compartment 11. The feed actuating shaft 46 is intermittently turned by a one-way clutch 47, which may be of any suitable construction, having an actuating-arm 48 connected by a link 49 to the lower end of an angle lever 50 journaled upon a stationary fulcrum-stud 51 fixed in a lug 52 integral with the machine-frame 1. The angle lever 50 is oscillated upon the fulcrum-stud 51 by an adjustable feed-eccentric 53 through the pitman connection 54. Any form of adjustable eccentric may be used, but I prefer to employ the type disclosed in the U. S. Patent of P. Diehl et al. No. 814,027, issued Mar. 6, 1906. Access to the adjustable eccentric 53 may be had by removing the screw-plug 55 in the standard 2. The provision of the adjustable eccentric permits a regulation of the extent of oscillation imparted to the actuating-arm 48 of the one-way clutch by the link 49, angle lever 50 and pitman 54. Inasmuch as the turning movement imparted to the feed-actuating shaft 46 is determined by the extent of oscillation imparted to the one-way clutch, and since the feed-actuating shaft 46 is operatively connected to the feed-shaft 37 by the spur gears 44 and 45 and to the feed-shaft 60 by the clip-belt 33, it follows that a change in the eccentricity of the eccentric will effect a change in the degree of turning movement imparted to the feed-cups 6 and 7.

From Fig. 3, it will be observed that the fulcrum-stud 51 is threaded into the lug 52 and is held against turning by a set-screw 56. To prevent movement of the hub of the elbow lever 50 lengthwise of the fulcrum-stud 51, a collar 57 is secured upon the inner end of the fulcrum-stud 51.

Referring now to Figs. 4 and 5, the feed-actuating shaft 46 has secured upon its upper end a grooved belt-pulley 58 which is connected by a common form of clip-belt 33 to a second, or outer, grooved belt-pulley 59 fastened upon the upper end of a vertically depending feed-shaft 60 supporting at its lower end the outer feed-cup 7. The two belt-pulleys 58 and 59 are preferably constructed of a soft material, such as fiber or the like, to minimize wear and noise. The depending feed-shaft 60 is journaled in spaced bearings provided in the opposite ends of a stationary, tubular housing or sheath 61 which is clamped at its upper end by screw 62 in the split end 63 of the pivotally mounted feed-cup supporting lever 34. From the above description, it will be understood that the two feed-cups 6 and 7 are intermittently rotated simultaneously to advance the material in one direction, and that the degree of movement imparted to the feed-cups per turn of the main-shaft 46 is determined by the adjustable feed eccentric 53.

The trimming instrumentalities per se comprise a stationary ledger blade and a movable cutting blade to cooperate therewith in severing the material fed through the machine by the feed-cups.

The ledger blade 64 (Figs. 7 and 8) is supported on a bracket 65 secured to the lower end of feed-shaft housing 61, being rigidly held by a clamping plate 66 and screws 67. The cutting end 68 of the ledger blade, of which end the upper edge constitutes the cutting edge, is preferably of arcuate form and the blade is so located that a portion of the cutting edge is in the plane of tangency of the feed-cups. As shown in Fig. 7, approximately the mid-point of the cutting edge is substantially directly above the tangent point of the feed-cups. As shown in Fig. 9, the arcuate cutting end of the ledger blade substantially registers with the upper peripheral edge of the outer feed-cup 7.

Correspondingly located adjacent the upper peripheral edge of the inner feed-cup 6 is an arcuate guide-finger 69 secured by screws 70 to bracket 71. As shown in Fig. 2, the bracket 71 is secured to the face of the standard 2 by screws 72. The thickness of finger 69 is such that its upper face is in the plane of the top face of the ledger blade 64. The convexly curved edge 69' of the finger 69 is preferably substantially in vertical register with the work-engaging face of the feed-cup 6; said edge 69' being in part opposed to the cutting end 68 of the ledger-blade.

The movable cutting member comprises a blade 73 having a cutting edge 74 which is preferably inclined to the plane of tangency of the feed-cups. Adjacent the cutting edge 74, the blade has a projecting finger 75 which extends across the plane of tangency of the feed-cups and bears upon the ledger-blade 64. To maintain the cutting blades in effective cutting relation, the movable blade is yieldingly urged downwardly into pressure contact with the ledger-blade.

Slidably mounted in the upper and lower spaced arms 76 and 76' of a bifurcated bracket 77 is a tubular carrier shaft 78 which is internally threaded to receive a long clamping screw 79.

The clamping screw engages a shoe 80 which bears upon the top of the cutting blade 73. From the underside, the latter is supported by a plate 81 which is secured by screws 82 to the enlarged base portion 83 of carrier shaft 78. Bridging the arms 76 and 76' and secured thereto by screws 84, 85 is a guide plate 86 which is straddled by the flanges 87 of a collar 88 secured by set screw 89 to carrier shaft 78. The latter and the movable blade supported thereby are thus held against turning relatively to the bracket 77. A spring 90, acting on the top of collar 88 and bearing against the underside of the arm 76, serves to maintain the cutting blade 73 in contact with the ledger-blade. To this end, the blade 73 is preferably 15 slightly spaced vertically from the guide-finger 75.

The cutting edge 74 of the cutting blade 73 is arranged to intersect the plane containing both axes of rotation of the feed-cups and is adapted to be reciprocated in such plane for work-severing coaction with the ledger-blade. In the result, and by reason also of the above-described arrangement and location of the ledger-blade, the cutting of the material is effected substantially 20 at the point of tangency of the feed-cups, at which point the material to be trimmed is most firmly held and presented to the ledger and cutting blades. The curved edge 69' of the finger 69 not only functions in helping to direct the work between the feed-cups, but said edge 69' also serves to support the work against lateral movement between the blade 73 and the upper edge of the feed-cup 6, whereby skewing of the work is obviated.

Referring now to Figs. 3 and 4 and the means by which the cutting blade is reciprocated, it will be seen that the bracket 77 is formed upon or secured to the end of a horizontally disposed reciprocating knife-bar 91, journaled in bushings 92 and 93 fixed in the machine-frame. To effect a stripping of the oil from the bar 91 as it reciprocates in the housing 92, the bearing surface of the latter has an annular recess 94 cut therein, which recess at its bottom opens into an oil-return groove 95 in the bushing 92 which directs any excess oil collected in the recess 94 back into the splash-lubrication compartment 11.

The bar 91 intermediate its ends has clamped thereto, by means of a screw 96, a collar 97 provided with an upstanding guide-lug 98 adapted to slide in a guideway between gibs 99 secured to the bottom of the horizontal partition 10 by screws 100. The function of the guide-lug 98 is to provide means for preventing the bar 91 from turning in its bearings as the same is reciprocated. Depending from the collar 97 is a lug 101 connected by a link 102 to the upper arm of a rock-lever 103 having an elongated hub 104, see Fig. 7, journaled between collars 105 upon a fulcrum rod 106 fixed in spaced lugs 107 formed upon the standard 2. Connected to the lower arm of the lever 103 is a pitman 108 which is connected at its other end to a crank 109 formed in the main-shaft 16. As shown in Fig. 4, the rear wall of the machine-frame is provided with a removable screw-plug 110 which can be removed to permit assembly of the bar 91 in its bearings.

To facilitate the introduction of the work between the two feed-cups, means is provided whereby the outer feed-cup 7 can be shifted away from the inner feed-cup 6. This means comprises the feed-cup supporting lever 34 which, as previously described, has clamped in its split forward end 63 the sheath 61 in which is journaled the feed-shaft 60. The feed-cup supporting

lever 34, Figs. 4 and 5, adjacent its forward end is formed with two spaced bearing lugs 111 and 112 which are apertured to receive pivot-studs 113 and 114. Pivot-stud 113 is secured by a screw 115 in a supporting bracket 116 fastened by screws 117 upon the bottom wall of the belt compartment 12 and the pivot-stud 114 is secured by screw 118 in a boss 119 cast integral with the machine-frame 1. The two bearing lugs 111 and 112 are spaced to provide a clearance for the clip-belt 33.

At the inner end of the feed-cup supporting lever 34 (see Figs. 4 and 5) there is formed an offset lug 120 and at right angles to the main body of the supporting lever 34 a stop-arm 121 adapted to be received between two adjustable stop-bars 122 and 123, which limit the extent of movement of the outer feed-cup 7 toward and away from the inner feed-cup 6. It will be observed in Fig. 4 that the upper stop-bar 122 is threaded upon the adjusting screw 124 and is guided by the second adjusting screw 125, while the lower stop-bar 123 is threaded upon the second adjusting screw 125 and guided by the first adjusting screw 124. By having the upper stop-bar 122 adjustable, the outer feed-cup 7 may be initially set at various distances from the inner feed-cup 6 depending upon the thickness of the material being trimmed. After the stop-bar 122 has been correctly set, the lower stop-bar 123 can be adjusted to limit movement of the outer feed-cup in a direction away from the inner feed-cup. In order to facilitate assembly, the two adjusting screws 124 and 125 are reduced at their lower ends and set into apertures 126 drilled in the machine-frame, the screws 124 and 125 being maintained seated in these apertures 126 by the cover-plate 8 which rests upon the flanges 127 formed upon the heads of the adjusting screws 124 and 125.

Referring now to Fig. 3, it will be seen that the offset lug 120 provided at the inner end of the feed-cup supporting lever 34 is apertured and dished, as at 128, to receive the semi-spherical nut 129 threaded upon the upper end of a control rod 130 connected at its lower end preferably by a chain to a knee-control or foot-treadle (not shown). The control-rod 130 extends through a tubular housing or sheath 131 which at its lower end is pressed into an aperture in an upstanding boss 132 integral with the bottom plate 13 and at its upper end extends through an aperture in the wall 10 of the machine-frame. The housing 131 provides an oil-seal and eliminates leakage of oil from the splash-lubrication compartment 11.

Means is provided for maintaining the outer feed-cup in its lowered or operative position and this means comprises a coil-spring 133 surrounding the control rod 130, the upper end of the spring bearing against the bottom of the offset lug 120 on the feed-cup supporting lever 34 and the lower end of the spring bearing on a washer 134 at the top of a tubular spacer member 135 within the housing 131. The bottom of the tubular spacer member 135 is in engagement with the top of an adjusting sleeve 136 threaded into the boss 132. The adjusting sleeve 136 at its lower end is formed with a knurled head 137 and has threaded upon its shank a locking nut 138 for securing the adjusting sleeve in any set position. From the above description, it will be understood that the coil-spring 133 yieldingly maintains the stop-arm 121 in contact with the upper stop-bar 122 which initially positions the outer feed-cup

7 a definite distance from the inner feed-cup 6, and that the tension of the coil-spring 133 can be regulated by the adjusting sleeve 136.

When the machine illustrated is used for certain operations, such as trimming hosiery or other material the edges of which have a pronounced tendency to curl, it is desirable to employ a so-called uncurling guide which flattens the edges of the material and presents them to the cutting mechanism in distended form appropriate for trimming.

One form of uncurling guide, generally designated 139, is shown in Figs. 1 and 2. It is mounted on a bracket 140 secured to the machine frame by a screw 141 and includes a central guiding plate 142 terminating at its upper end in a supporting shank 143. Disposed on opposite sides of the guiding plate 142 are uncurlers 144 and 145 yieldingingly pressed against the faces of the guiding plate, as by springs 146. The construction of uncurlers of this general character is well known, and since the details of the uncurler illustrated form no part of the present invention, no further description is necessary.

However, it will be recognized that by reason of the above-described arrangement of the ledger and cutting blades, whereby the trimming takes place substantially at the point of tangency of the feed-cups, the uncurling guide, of whatever particular construction, can be mounted extremely close to such point of tangency, thereby further contributing to the effectiveness of the machine, particularly at high speed. As appears in Fig. 7, the uncurling guide is mounted between the feed cups adjacent and immediately in advance of the trimming blades.

Having thus set forth the nature of the invention, what I claim herein is:

1. In a trimming machine, including opposed rotary feed-cups adapted to grip and feed the material to be trimmed, the improvement which comprises the combination of a ledger blade mounted adjacent one of the feed-cups with a portion of its cutting edge substantially in the plane of tangency of the feed-cups, and a movable cutting blade to cooperate with the ledger blade in trimming the material fed by said cups, said cutting blade having its cutting edge located to cross the cutting edge of the ledger blade at a point lying substantially in the plane of the axes of rotation of the feed-cups.

2. In a trimming machine, including a pair of rotary feed-cups adapted to grip and feed the material to be trimmed, the improvement which comprises the combination of a ledger blade mounted adjacent one of the feed-cups with a portion of its cutting edge substantially in the plane of tangency of the feed-cups, a cutting blade adapted to cooperate with the ledger blade in trimming material fed by said cups, and means to reciprocate the cutting blade, said cutting blade having its cutting edge so located with reference to its path of reciprocation as to coact with the cutting edge of the ledger blade at a point lying substantially in the plane of the axes of rotation of the feed-cups.

3. In a trimming machine, including a pair of feed-cups disposed for rotation about vertical axes and adapted to grip and feed the material to be trimmed, the combination therewith of a ledger blade mounted above and adjacent one of the feed-cups with a portion of its cutting edge substantially overlying the point of tangency of the feed-cups, and a movable cutting blade to cooperate with the ledger blade, said movable cutting

blade being mounted above and adjacent the other feed-cup with its cutting edge located to cross the cutting edge of the ledger blade also at a point substantially overlying the point of tangency of the feed-cups.

4. In a trimming machine, including a pair of rotary feed-cups adapted to grip and feed the material to be trimmed, the improvement which comprises the combination of a ledger blade, having an arcuate cutting edge overlying and substantially registering with a peripheral edge of one of the feed-cups at the point of tangency of such cup with its adjacent cup, and a movable cutting blade to cooperate with the ledger blade in trimming the material fed by said cups, said cutting blade having its cutting edge located to cross the cutting edge of the ledger blade at a point lying substantially in the plane of the axes of rotation of the feed-cups.

5. In a trimming machine, including a pair of rotary feed-cups adapted to grip and feed the material to be trimmed, the improvement which comprises the combination of a ledger blade mounted adjacent one of the feed-cups with its cutting edge disposed transversely of the axes of rotation of said feed-cups and having a portion of its cutting edge substantially in the plane of tangency of the feed-cups, and a movable cutting blade, said cutting blade having supporting means extending across the said plane of tangency of the feed-cups.

6. In a trimming machine, including a pair of rotary feed-cups adapted to grip and feed the material to be trimmed, the improvement which comprises the combination of a ledger blade mounted adjacent one of the feed-cups with its cutting edge disposed transversely of the axes of rotation of said feed-cups and having a portion of its cutting edge substantially in the plane of tangency of the feed-cups, a movable cutting blade to cooperate with the ledger blade in trimming the material fed by said cups, and means adapted to support the cutting blade on the ledger blade throughout the entire movement of the cutting blade.

7. In a trimming machine, including a pair of rotary feed-cups adapted to grip and feed the material to be trimmed, the improvement which comprises the combination of a ledger blade mounted adjacent one of the feed-cups with its cutting edge disposed transversely of the axes of rotation of said feed-cups and having a portion of its cutting edge substantially in the plane of tangency of the feed-cups, a movable cutting blade to cooperate with the ledger blade in trimming the material fed by said cups, and means for supporting the cutting blade on both sides of the plane of tangency of the said feed-cups.

8. In a trimming machine, including a pair of rotary feed-cups adapted to grip and feed the material to be trimmed, the improvement which comprises the combination of a ledger blade mounted adjacent one of the feed-cups with its cutting edge disposed transversely of the axes of rotation of said feed-cups and having a portion of its cutting edge substantially in the plane of tangency of the feed-cups, a movable cutting blade to cooperate with the ledger blade in trimming the material fed by said cups, and means for supporting the cutting blade immediately adjacent the cutting edge of the ledger blade and on both sides of the plane of tangency of the said feed-cups.

9. In a trimming machine, including a pair of

rotary feed-cups adapted to grip and feed the material to be trimmed, the improvement which comprises the combination of a ledger blade mounted adjacent one of the feed-cups with a portion of its cutting edge substantially in the plane of tangency of the feed-cups, a movable cutting blade to cooperate with the ledger blade in trimming the material fed by said cups, and means for resiliently supporting the cutting blade on the ledger blade.

10. In a trimming machine, including a pair of rotary feed-cups adapted to grip and feed the material to be trimmed, the improvement which comprises the combination of a ledger blade mounted adjacent one of the feed-cups with a portion of its cutting edge substantially in the plane of tangency of the feed-cups, a cutting blade to cooperate with the ledger blade in trimming the material fed by the cups, and means to reciprocate the cutting blade in the plane of the axes of rotation of the feed-cups.

11. In a trimming machine, including a pair of rotary feed-cups adapted to grip and feed the material to be trimmed, the improvement which comprises the combination of a ledger blade mounted adjacent one of the feed-cups with a portion of its cutting edge substantially in the plane of tangency of the feed-cups, a cutting blade to cooperate with the ledger blade in trimming the material fed by the cups, resilient supporting means for said cutting blade, and means to reciprocate said supporting means in the plane of the axes of rotation of the feed-cups.

12. In a trimming machine, including a pair of rotary feed-cups adapted to grip and feed the material to be trimmed, the improvement which comprises the combination of a ledger blade mounted adjacent one of the feed-cups with a portion of its cutting edge substantially in the plane of tangency of the feed-cups, a cutting blade to cooperate with the ledger blade in trimming the material fed by the cups, the cutting blade having its cutting edge located to intersect the plane of the axes of rotation of the feed-cups, and means to reciprocate the cutting blade in such plane.

13. In a trimming machine, including a pair of rotary feed-cups adapted to grip and feed the material to be trimmed, the improvement which comprises the combination of a ledger blade mounted with a portion of its cutting edge substantially in the plane of tangency of the feed-cups and substantially coincident with a peripheral edge portion of one of such cups, a guide-member mounted adjacent the other of such cups with a surface substantially aligned with a surface of the ledger blade, and a movable cutting blade to cooperate with the ledger blade, said cutting blade having a supporting portion adapted to ride on said surface of the ledger blade throughout the entire movement of the cutting blade.

14. In a trimming machine, including a pair of rotary feed-cups adapted to grip and feed the material to be trimmed, the improvement which comprises the combination of a ledger blade mounted with a portion of its cutting edge substantially in the plane of tangency of the feed-cups and substantially coincident with a peripheral edge of one of such cups, a guide-member mounted adjacent the other of such cups with a

surface substantially aligned with a surface of the ledger blade, and a movable cutting blade to cooperate with the ledger blade, said cutting blade being resiliently supported on one of said surfaces.

15. In a trimming machine a frame including a standard and an overhanging bracket, a pair of feed-cups mounted to rotate in a horizontal plane beneath said bracket, a drive shaft for one of the feed-cups and a stationary housing for said shaft depending from said bracket, a reciprocatory knife-bar mounted in the standard, a ledger blade mounted on said drive shaft housing, and a cooperating cutting blade mounted on said reciprocatory knife-bar.

16. In a trimming machine a frame including a standard and an overhanging bracket, a pair of feed-cups mounted to rotate in a horizontal plane beneath said bracket, a drive shaft for one of the feed-cups and a stationary housing for said shaft depending from said bracket, a ledger blade mounted on said drive shaft housing with a portion of its cutting edge substantially in the plane of tangency of the feed-cups, a cooperating cutting blade, and means disposed in the standard for reciprocating the cutting blade in the plane of the axes of rotation of the feed-cups.

17. In a trimming machine, the combination with a pair of rotary feed-cups adapted to grip and feed the material to be trimmed, a ledger blade mounted adjacent one of the feed-cups with a portion of its cutting edge located substantially at a point of intersection of the plane of rotation of the axes of the feed-cups with the plane of tangency of the feed-cups, and a movable cutting blade to cooperate with the ledger blade, the cutting edge of said cutting blade having a path of movement to sever the material substantially at the said point of intersection.

18. In a trimming machine, the combination with a pair of rotary feed-cups adapted to grip and feed the material to be trimmed, a ledger blade mounted adjacent one of the feed-cups with a portion of its cutting edge located substantially at a point of intersection of the plane of rotation of the axes of the feed-cups with the plane of tangency of the feed-cups, a movable cutting blade adapted to cooperate with the ledger blade to sever the material substantially at the said point of intersection, and an uncurling guide located between the feed-cups adjacent and in advance of said blades.

19. In a trimming machine, a pair of opposed and relatively yieldable outer and inner feed-cups disposed for rotation about vertical axes, means for rotating said feed-cups, a ledger blade disposed above and in close proximity to the outer one of said feed-cups, said ledger blade having a cutting edge, a coacting movable cutting blade having a horizontal path of reciprocation above the inner of said feed-cups and across the cutting edge of said ledger blade at the upper side of said ledger blade, means for reciprocating said movable cutting blade, and a guide member disposed between said movable cutting blade and the inner of said feed-cups, said guide-member having a fabric-guiding edge opposed to the cutting edge of said ledger blade and disposed substantially in vertical register with the work-engaging face of said inner feed-cup.

HANS HACKLANDER.
